United States Patent Office.

J. S. McKAYE AND H. G. MCKAY, OF NEW YORK, N. Y.

Design No. 2,717, dated August 6, 1867.

DESIGN FOR A STATUETTE.

The Schedule referred to in these Letters Patent and making part of the same.

TO ALL WHOM IT MAY CONCERN:

Be it known that we, J. S. McKAYE and H. G. MCKAY, of the city, county, and State of New York, have originated a Design for a Statuette; and we do hereby declare that the following is a full, clear, and exact description thereof, reference being had to the accompanying drawing forming part of this specification.

The present invention relates to a design for a statuette of D. G. Farragut, Admiral of the naval forces of the United States of America.

This design is illustrated in the accompanying plate by a photographic view of the statuette, and consists of a pedestal, A, of a suitable form and size, upon the top of which stands the figure, in full length, of Admiral D. G. Farragut, in a position, with head B slightly turned to one side, and with the arms C down, carrying in one hand D the sheathed sword E, and in the other a naval cap, F. The coat G is represented as closely buttoned up, and encircled by a body-belt H, of the regulation standard, in all instances.

Having thus described our invention, what we claim as new, and desire to secure by Letters Patent, is—
The design for a statuette, substantially as described and shown.

The above specification of our invention, signed by us this   day of June, 1867.

J. S. MCKAYE,
H. G. MCKAY.
